(57) CLAIM

The ornamental design for a football tee, as shown and described.

DESCRIPTION

FIG. 1 shows a top view of the football tee embodying our claimed design.

FIG. 2 shows a right, rear perspective view thereof.

FIG. 3 shows a right side view thereof the left side view being a mirror image.

FIG. 4 shows a rear view thereof.

FIG. 5 shows a front view thereof.

FIG. 6 shows a bottom view thereof.

FIG. 7 shows a view similar to that of FIG. 5 and showing in broken lines a first possible orientation of a football on the claimed tee.

FIG. 8 shows a view similar to that of FIG. 3 and showing in broken lines a second possible orientation of a football on the claimed tee.

FIG. 9 shows a view similar to that of FIG. 8 and showing in broken lines a third possible orientation of a football on the claimed tee; and,

FIG. 10 shows a view similar to that of FIGS. 8 and 9 and showing in broken lines a fourth possible orientation of a football on the claimed tee.

The broken lines showing the football in FIGS. 7-10 are included for the purpose of illustrating the intended use of the football tee and form no part of the claimed design.
